OSCILLATOR CONTROL CIRCUIT

Donald L. Hings, Ottawa, Ontario, Canada

Application May 3, 1944, Serial No. 533,861

In Canada April 24, 1944

9 Claims. (Cl. 250—36)

1.

My invention relates in general to radio frequency circuits and more particularly to circuits for controlling the oscillations of an oscillator tube.

An object of my invention is to provide for starting and stopping a crystal oscillator at high speeds.

Another object of my invention is to provide for switching crystals without mechanical means.

Another object of my invention is to provide for selectively switching crystals by electronic means.

Another object of my invention is to provide for controlling crystals by wave forms and by a variable control voltage device.

Another object of my invention is to provide for interchanging operation of crystals at high speeds.

Another object of my invention is to provide for controlling an oscillator with a multiple of crystals.

Another object of my invention is to provide for the remote control of the selection of crystals without mechanical means.

Another object of my invention is to prevent overloading of crystals in an oscillator.

Another object of my invention is to permit more than one crystal to oscillate with a single oscillating tube.

Another object of my invention provides for stopping and starting a crystal oscillator without changing the supply potentials to the tube.

Other objects and a fuller understanding of my invention may be had by referring to the following description and claims taken in conjunction with the accompanying drawing in which,

Figure 1 is a circuit embodying the features of my invention;

Figure 2 is a circuit showing an extension of the circuit in Figure 1.

With reference to Figure 1, my circuit comprises generally an oscillator tube 20 which is controlled by a control tube 19. The oscillator tube 20 comprises a cathode 2, a control grid 3, a screen grid 4, and a plate 5. The plate 5 is connected to the positive potential of a direct current source through a plate choke 9 which has a swamping resistance 10 connected parallel therewith. The screen grid 4 is connected to the positive potential of the direct current source. The cathode 2 is connected to the negative potential of the direct current source. The screen grid 4 is by-passed to ground through the capacitor 8. The control grid 3 is biased by means of a battery 13 which is connected in series with

2.

a grid leak 7. Between the plate 5 and the control grid 3, I provide for mounting a crystal 21 and a variable voltage feed-back capacitor 6 which is arranged to be adjustable. The oscillator circuit, as described, will oscillate at a frequency determined by the characteristics of the crystal 21. The plate 5 of the oscillator tube 20 is arranged to deliver power to any suitable load as indicated by the arrow.

The control tube 19 comprises a cathode 14, a control grid 15 and a plate 16 which is connected to the upper side of the variable voltage feed-back capacitor 6. The cathode 14 is connected to the opposite side of the variable voltage feed-back capacitor 6. The cathode 14 is maintained at radio frequency potentials above ground by means of the combination of a cathode choke 11 having in parallel therewith a swamping resistance 17. The intermediate portion of the cathode choke 11 and the intermediate portion of the swamping resistance 17 may be connected together. The control grid 15 is by-passed to ground for radio frequency through a capacitor 12. The control grid 15 is governed by a variable control voltage device indicated by the reference character 23.

Under the condition of operation to render the oscillator tube 20 operative for generating a radio frequency as determined by the characteristics of the crystal 21, the control grid 15 is biased to cut-off. In other words, when the control grid 15 is biased to cut-off no current flows between the cathode 14 and the plate 16 with the result that the capacitor 6 and the crystal 21 operate substantially the same as if the control tube were not in the circuit. Accordingly, the oscillator tube 20 functions to produce oscillations which are governed substantially solely by the capacitor 6 and the crystal 21.

To render the oscillator tube 20 inoperative or to reduce the strength of the oscillations, the control grid 15 is biased more positive through the variable control voltage device 23. Under this condition current flows in the cathode-to-plate circuit of the control tube 19 and impresses a voltage in opposite phase upon the feed-back capacitor 6 which tends to neutralise the feed-back energy delivered to the capacitor by the oscillator circuit. The oscillator tube 20 is arranged to be rendered completely inoperative by biasing the control grid 15 to a predetermined positive bias by the variable control voltage device 23. It is also within the scope of my invention to vary the degree of the bias of the control grid 15 whereby the neutralising effect imposed

upon the capacitor 6 is not completely cancelled, with the result that the oscillator tube 20 operates with a reduced amplitude.

The variable control voltage device may include a number of arrangements depending upon the use to which my circuit is employed. Thus for example the bias of the control grid 15 may be governed by any one of the following arrangements; namely, by a telegraph key; by a telegraph key with tone modulating waves; by voice modulating waves; by voice modulating waves with voice control bias; and by frequencies of any wave form. Each of these variable control voltage devices may be located at a remote point from the terminals A and B which enables me to obtain control of the control tube 15 by remote operation. With reference to a telegraph key, each time that the operator depresses the key the bias on the control tube 15 becomes more negative and permits the crystal 21 to oscillate. For telegraph key with tone modulating waves, the control grid 15 is first biased negative upon the key being depressed, after which the crystal 21 oscillates at amplitudes governed by the tone generator. For voice modulating waves, the control grid 15 is biased so that the crystal oscillates at a limited amplitude which is varied by voice modulating waves. For voice modulating waves with voice control bias, the control grid 15 receives in combination voice modulating waves and resulting negative bias from rectifications of these waves which permits the crystal to start oscillating and to vary in amplitude with the modulating waves simultaneously. The bias returns positive with the termination of the modulating waves which stops the crystal oscillating. In other words this arrangement is characterized as a voice operated carrier.

In addition to controlling the oscillations of the oscillator tube 20, the control tube 19 functions to limit or regulate the voltage impressed upon the crystal 21. This regulation is brought about through the circuit arrangement between the crystal 21 and the control grid 15, in that when the voltage amplitude upon the crystal 21 tends to become too great by means of varying load values, the control grid 15 becomes operative because of the increased cathode voltage on the cathode 14 and thereby causes the control tube 19 to pass current and impress a voltage in opposite phase upon the capacitor 6 to decrease the voltage thereon which in turn limits the voltage impressed upon the crystal 21.

In Figure 2 I show an extension of the circuit in Figure 1, whereby the oscillator tube 20 is governed by two crystals. The portion of the circuit to the right of the vertical dotted line is substantially the same as that shown in Figure 1 and the portion of the circuit to the left of the vertical dotted line represents the added part. The portion of the circuit to the left of the vertical line is a control circuit having substantially identical parts to the control circuit indicated in Figure 1. The corresponding component parts to the left of the vertical line have reference characters which are higher in number by 30 over those shown to the right of the vertical line. Thus for example the control tube to the left of the vertical line is designated by the reference character 49 which is higher than the reference character 19 by a value of 30. The control grid 15 in Figure 2 is controlled by the variable control voltage device between A and B and the control grid 45 or the control tube 49 is governed by the variable control voltage device between A and C. The

oscillations of the oscillator tube 20 are governed respectively by the crystal 21 and the crystal 51. With the dual arrangement of control circuits, the crystals 21 and 51 are selectively governed by electronic means to vary the oscillations of the oscillator tube 20. Thus for example the oscillator tube 20 oscillates at a frequency governed by the characteristics by the crystal 21 when the variable control voltage device between A to B is operated and the oscillator tube 20 oscillates at a frequency governed by the characteristics of the crystal 51 when the variable control voltage device between A and C is operated. Under one set of circuit conditions, the oscillator tube 20 oscillates in accordance with the characteristics of the crystal 21. Under a second set of conditions the oscillator tube 20 oscillates in accordance with the characteristics of the crystal 51. Under another set of conditions the oscillations of the oscillator tube may be stopped when both of the crystals 21 and 51 are made inoperative by their respective control tubes, and under a fourth condition the oscillator tube 20 may oscillate simultaneously at two frequencies which are governed respectively by the crystals 21 and 51.

While I have shown in Figure 2 two variable control voltage devices; namely, between A to B and A to C, it is to be understood my system may be extended to include a larger number of such variable control voltage devices together with their related control tubes and crystals. The operation of the crystals 21 and 51 are independent of each other and their frequency values may be relatively close or far apart or they may be of the same frequencies. The fast alternation or interchange of crystals permits multiplex operation when individually operated in groups of pulses. This arrangement does not require synchronization at the receiving point.

Although I have shown and described my invention with a certain degree of particularity, it is understood that the present disclosure has been made only by way of example and numerous changes in the details of construction and the combination and arrangement of parts may be resorted to without departing from the spirit and the scope of the invention as hereinafter claimed.

I claim as my invention:

1. A radio frequency system comprising an oscillator circuit including at least an oscillator tube, said oscillator tube having at least a cathode, a plate and a control element, said cathode being connected to a point of reference potential, impedance means connected between said plate and said point of reference potential, a crystal and a capacitor connected in series between the plate and the control element for controlling the oscillations of the oscillator tube, said capacitor having a first terminal connected to said plate and a second terminal connected to said crystal, a control tube having at least a cathode, a plate and a control element, means including impedance means for connecting the cathode of the control tube to said point of reference potential, first circuit means for connecting the plate of the control tube to the first terminal of the capacitor, second circuit means for connecting the cathode of the control tube to the second terminal of the capacitor, and variable voltage means for varying the bias of the control element of the control tube and thereby governing the oscillations of the oscillator tube.

2. A radio frequency system comprising an oscillator circuit including at least an oscillator tube having at least plate, cathode and control ele-

ments, said cathode element being connected to a point of reference potential, first reactance means connected between said plate element and said point of reference potential, second reactance means connected between two of said three elements and subject to a feedback voltage to sustain oscillation, a control tube having at least anode, cathode and control means, means including impedance means for connecting the cathode means to said point of reference potential, connection means for connecting said second reactance means across said anode and cathode means, and variable voltage means for varying the bias of the control means thereby governing the oscillations of the oscillator tube.

3. A radio frequency system comprising an oscillator circuit including at least an oscillator tube having at least plate, cathode and control elements, said cathode element being connected to a point of reference potential, first reactance means connected between said plate element and said point of reference potential, a crystal, second reactance means connected in series with said crystal across two of said three elements and subject to a feedback voltage to sustain oscillation, a control tube having at least anode, cathode and control means, means including impedance means for connecting the cathode means to said point of reference potential, connection means for connecting said second reactance means across said anode and cathode means, and variable voltage means for varying the bias of the control means thereby governing the oscillations of the oscillator tube.

4. A radio frequency system comprising an oscillator circuit including at least an oscillator tube having at least plate, cathode and control elements, said cathode element being connected to a point of reference potential, reactance means connected between said plate element and said point of reference potential, a crystal, capacitance means connected in series with said crystal across two of said three elements and subject to a feedback voltage to sustain oscillation, a control tube having at least anode, cathode and control means, means including impedance means for connecting the cathode means to said point of reference potential, connection means for connecting said capacitance means across said anode and cathode means, and variable voltage means for varying the bias of the control means thereby governing the oscillations of the oscillator tube.

5. A radio frequency system comprising an oscillator circuit including at least an oscillator tube having at least a cathode, a plate and a control element, said cathode being connected to a point of reference potential, a first impedance device connected between the plate and the point of reference potential, a branch circuit including a second and a third impedance device for interconnecting said cathode, plate and control element, said second impedance device having a first and second terminal, first connection means for connecting said first terminal of the second impedance device to the said plate, second connection means for connecting the said second terminal of the second impedance device to the said control element, third connection means for connecting the said third impedance device between the second terminal of the second impedance device and the point of reference potential, a control tube having at least a cathode, a plate, and a control element, first circuit means for connecting the plate of the control tube to the first terminal of the second impedance device, second

circuit means for connecting the cathode of the control tube to the second terminal of the second impedance device, and variable voltage means for varying the bias of the control element of the control tube and thereby govern the oscillations of the oscillator tube.

6. A radio frequency system comprising an oscillator circuit including at least an oscillator tube having at least a cathode, a plate and a control element, said cathode being connected to a point of reference potential, a first impedance device connected between the plate and the point of reference potential, a branch circuit including a crystal and a second and a third impedance device for interconnecting said cathode, plate and control element, said second impedance device having a first and second terminal, first connection means for connecting said first terminal of the second impedance device to the said plate, second connection means for connecting the said crystal between the second terminal of the second impedance device and the said control element, third connection means for connecting the said third impedance device between the second terminal of the second impedance device and the point of reference potential, a control tube having at least a cathode, a plate, and a control element, first circuit means for connecting the plate of the control tube to the first terminal of the second impedance device, second circuit means for connecting the cathode of the control tube to the second terminal of the second impedance device, and variable voltage means for varying the bias of the control element of the control tube and thereby govern the oscillations of the oscillator tube.

7. A radio frequency system comprising an oscillator tube having a plate, a cathode, a control grid and a screen grid, first impedance means connected between said screen grid and said plate, direct current potential means connected to said screen grid, said cathode being connected to a point of reference potential, first oscillator frequency by-pass means connected between said screen grid and said point of reference potential, a capacitor and a crystal connected in series between said plate and said control grid, said capacitor having a first terminal connected to said plate and a second terminal connected to said crystal, second impedance means and biasing means connected between said control grid and said cathode, a control tube having anode means, cathode means and control means, connection means for connecting said capacitor across said anode and cathode means, means including third impedance means for connecting said cathode means to said point of reference potential, second oscillator frequency by-pass means connected between said control means and said point of reference potential, and variable voltage means connected across said second oscillator frequency by-pass means.

8. A radio frequency system comprising an oscillator circuit including at least an oscillator tube, said oscillator tube having at least a cathode, a plate and a control element, said cathode being connected to a point of reference potential, impedance means connected between said plate and said point of reference potential, a first and second crystal and a first and second capacitor, first connection means for connecting said first crystal and capacitor in series between the plate and the control element for controlling the oscillations of the oscillator tube, second connection means for connecting said second crystal and

capacitor in series between the plate and the control element for controlling the oscillations of the oscillator tube, said capacitors having a first terminal connected to said plate and a second terminal connected to said correspondingly numbered crystals, first and second control tubes having at least a cathode, a plate and a control element, means including impedance means for connecting the respective cathodes of the control tubes to said point of reference potential, first circuit means for connecting the plates of the control tubes to the first terminals of the capacitors, second circuit means for connecting the cathodes of the control tubes to the second terminals of the respective capacitors, and first and second variable voltage means for varying the bias of the control elements of the first and second control tubes, respectively, said first and second control tubes being also controllably operable simultaneously by the first and second variable voltage means for controlling the oscillations of the oscillator tube.

9. A radio frequency system comprising an oscillator circuit including at least an oscillator tube having at least cathode, plate and control elements, said cathode being connected to a point of reference potential, first reactance means connected between said plate element and said point of reference potential, second and third reactance means connected in parallel between two of said three elements and subject to a feedback voltage to sustain oscillation, first and second control tubes each having at least anode, cathode and control means, means including impedance means for connecting the respective cathode means to the said point of reference

potential, first connection means for connecting the second reactance means across said anode and cathode means of the first control tube, second connection means for connecting the third reactance means across said anode and cathode means of the second control tube, and first and second variable voltage means for varying the bias of the control means of the first and second control tubes respectively, said first and second control tubes also being controllably operable simultaneously by said first and second variable voltage means for controlling the oscillations of the oscillator tube.
